UNITED STATES PATENT OFFICE.

STANHOPE BOAL, OF PIQUA, OHIO.

STOVE.

No. 916,660.

Specification of Letters Patent. Patented March 30, 1909.

Application filed August 31, 1907. Serial No. 390,956.

To all whom it may concern:

Be it known that I, STANHOPE BOAL, a citizen of the United States, residing at Piqua, in the county of Miami and State of Ohio, have invented certain new and useful Improvements in Stoves, of which the following is a specification.

My invention relates to an improvement in base burner stoves.

One of the objects of my invention is to provide a series of flues in the back and base of the stove in which preferably two outer flues are employed for downward circulation and an intermediate flue for an upward circulation of the products of combustion. These flues are separated from each other and from the rear portion of the stove, thereby providing an improved heating efficiency for the stove by increasing the area of the radiating surfaces.

Another object of my invention is to provide air passages having inlets above the base of the stove and leading to the air dome at the top portion of the stove.

Other features relate to structural improvements designed to strengthen the stove, and to provide a convenient and efficient distribution of the various parts, and particularly in placing the air circulating tubes at the rear of the stove supplying hot air to the hot air dome above the combustion chamber. The parts are also so arranged as to improve the general design of the stove with an increased efficiency.

The features of my invention will be more fully set forth in the description of the accompanying drawings forming a part of this specification in which:—

Figure 1 is a perspective view of my improved stove with the flues for controlling the products of combustion broken for a clear illustration. Fig. 2 is a view of the base portion of the stove and a cross section taken through the flues. Fig. 3 is a central vertical section through the base of the stove. Fig. 4 is a section taken on line *x*, *x*, Fig. 5. Fig. 5 is a central vertical section of the rear portion of the stove. Fig. 6 is a section taken on line *w*, *w*, Fig. 2, through the rear portion of the stove. Fig. 7 is a sectional perspective view of one corner of the stove illustrating the upper portion of the air passage leading into the air dome.

1, 2 and 3 represent the rear flues which form a continuation of the bottom flues 4, 5 and 6. The two outer flues being down flues

and the intermediate flue an up flue leading to the escape pipe.

7 represents the back of the stove, and the flues 1, 2 and 3 are individual isolated flues placed in rear of the back 7 and separated from one another and from the back, providing a heat radiating jacket space between the flues and back. By this arrangement the entire area of each flue constitutes a heat radiating surface for radiating the heat from the rear of the stove, and also into the jacket space 8 which freely communicates with the atmosphere.

The course of the products of combustion when the stove is used as a base burner is as follows:—9 represents the fire box and 10 the combustion chamber. The flues at their upper portion terminate or lead into the combustion chamber 10 as is clearly illustrated in Figs. 4, 5 and 6. 11 represents a damper for closing the passage way between the combustion chamber 10 and flue 2, and which when the stove is used as a base burner is in its closed position as shown in Figs. 4 and 5. The products of combustion pass through and in a downward course through the rear flues 1 and 3, as shown by arrows Fig. 6, thence through the base flues 4 and 6 shown in Fig. 2 leading into the base flue 5 thence upward through the central flue 2 to the off take flue 12.

To use the stove as a direct burner the damper is moved or thrown downward to open the passage from the combustion chamber 10 direct into the flue 2, and to the off take 12.

13 represents a regulator for regulating the draft, opening a passage way between the ash chamber 14 and flue 2.

In this class of stoves a hot air dome is provided at the top thereof with air passages leading from the lower portion of the stove into said hot air dome. These air passages are preferably constructed as follows:—15 represents tubes providing air passages formed at the rear corners of the stove projecting outwardly and adjacent to the down flues forming a continuation of the jacket space between the back and sides of the stove and the walls of the flues 1 and 3. These air passages terminate above the leg base and lead into the hot air dome 20 and do not take the heated air from the floor under the stove but receive their supply of air through openings 16 along the sides of the stove. Heretofore these air passages

received their air through openings at the bottom of the stove above the floor, thus taking away the heat from the floor which is deemed objectionable. Air passages as heretofore provided have been exposed at the back of the stove taking away a considerable portion of the heat radiating surface, and delivering more or less cold air to the air dome. By my construction these air circulating flues do not interfere with the size of the other flues, the entire width of the back being taken up by the hot air flues 1, 2 and 3 and these air circulating flues pass up at the sides where the products of combustion enter the two descending hot air flues, thereby heating the air passing through these to a high degree.

The organization of this stove further adds to the ornamental design and utilizes to the greatest advantage every inch of available space for increasing the radiating surface.

Another feature of improvement is the construction of the bottom of the hot air flues at the base of the stove. Great difficulty has been experienced with the warping and buckling of this base plate in the ordinary stove. To avoid this and likewise increase the heat radiating surfaces at the base of the stove I form the bottom plate 17, see Fig. 3, with transverse inverted conical ribs 18 forming a portion of the partition walls between the flues 4, 5 and 6. Likewise the same trouble has been experienced with the upper plate 21 forming the top of the flues and the base of the ash chamber, and to overcome the warping and buckling, I have provided the ribs 19 forming a support for the ash pan 22. By this construction of base flues the lower part of the ash chamber

sides and front are exposed to the intense heat that passes through the bottom flues making the entire sides and front from the leg to the top of the ash chamber radiating surfaces.

Having described my invention, I claim:—

1. In a stove of the class described, three independent vertical flues communicating with the combustion chamber, separated from each other and the rear wall of the stove, three horizontal flues in the base of the stove communicating respectively with said vertical flues at one end and open to each other at their opposite ends, means for closing the passage of the intermediate vertical flue from the combustion chamber, a hot-air dome, air pipes at the rear corners of the stove, provided with air inlets above the base of the stove, said pipes terminating in the said hot-air dome, substantially as described.

2. In a stove of the class described, a combustion chamber, three independent vertical flues communicating with the combustion chamber separated from each other and the rear wall of the stove, an ash chamber, a bottom plate provided with V-shaped ribs, division plates seated upon said ribs forming three base flues between the bottom plate and the ash chamber communicating respectively with said vertical flues at one end and open to each other at their opposite ends, substantially as described.

In testimony whereof, I have hereunto set my hand.

STANHOPE BOAL.
